UNITED STATES PATENT OFFICE.

HARRY W. CLARK, OF KANSAS CITY, KANSAS, ASSIGNOR OF ONE-THIRD TO FREDERICK C. POWELL, OF KANSAS CITY, KANSAS, AND ONE-THIRD TO SOL. I. WEDLANSKY, OF KANSAS CITY, MISSOURI.

CIGAR-LIGHTER.

1,147,784.

Specification of Letters Patent. Patented July 27, 1915.

Application filed May 27, 1914. Serial No. 841,245.

To all whom it may concern:

Be it known that I, HARRY W. CLARK, a citizen of the United States, residing at Kansas City, in the county of Wyandotte and State of Kansas, have invented certain new and useful Improvements in Cigar-Lighters, of which the following is a specification.

My invention relates to cigar lighters, 10 and, among other features, embodies a wick and manually-controlled sparking means for igniting said wick.

The objects of the invention are to provide a self-contained cigar-lighter, which may be 15 placed anywhere upon a counter or showcase; one that can be maintained at small cost; and one which is so constructed as not likely to get out of order.

In order that the invention may be fully 20 understood, reference will now be made to the accompanying drawing, in which:

Figure 1 is a side elevation of the device. Fig. 2 is a side elevation, enlarged, showing the upper end of the wick and the manually- 25 controlled igniting means adjacent thereto. Fig. 3 is a rear elevation of the parts disclosed by Fig. 1. Fig. 4 is a vertical section on line IV—IV of Fig. 3. Fig. 5 is a side elevation of a snuffer and several other ele- 30 ments of the invention adjacent to said snuffer.

In carrying out the invention, I employ a tank or receptacle 1, for gasoline or other combustible material. Said receptacle has a 35 base 2 of sufficient size and weight to prevent the device from tipping over while in use. The receptacle 1 is filled through an opening normally closed by a cap 3, and said receptacle has an upwardly-extending tubu- 40 lar wick-holder 4 to which a rectangular extension 5 is secured, said rectangular extension being provided chiefly for convenience in assembling and supporting the ignition means.

6 designates a bearing secured to the extension 5 to support a rock-shaft 7, journaled in said bearing and provided at one end with a hand-wheel 8. The opposite end of the rock-shaft is provided with a fixedly- 50 mounted trigger 9 pivotally-connected at one end to the lower end of a connecting bar 10, which is pivotally-connected at its upper end to a snuffer 11, pivotally-mounted upon

a screw 12 engaging a bracket 13 secured to the upper end of the extension 5.

The forward end of the trigger 9 is normally held in contact with a stop 14 projecting from the adjacent side of one of a pair of cheek-plates 15, arranged at opposite sides of the extension 5 and pivotally-mounted upon the rock-shaft 7. The cheek-plates 15 are united by shouldered screws 16 and 17, the latter of which passes through a spacing-sleeve 18 abutting the inner sides of said cheek-plates, the backward pivotal movement of which is limited by said spacing sleeve contacting the extension 5, see Fig. 2.

19 designates a spring to accelerate the backward movement of the cheek-plates 15. Said spring 19 has its intermediate portion engaging a pin or screw 20 secured to the rock-shaft 7, about which a portion of the spring 19 is coiled. One end of the spring 19 engages the screw 16 and its opposite end bears against the adjacent side of the extension 5, see Fig. 2.

21 designates a latch to delay the forward movement of the cheek-plates 15 to allow spring 19 to become wound by turning the 80 rock-shaft 7 in the direction of the arrow, Fig. 2. Latch 21 is pivotally-connected to the adjacent cheek-plate 15 by a pin or screw 22, and normally engages a stationary pin 23 projecting from a plate 24 secured to the lower end of the rectangular extension 5 by screws 25. Latch 21 is provided at its upper end with a cam-shaped portion 26, which overlaps the adjacent end of the trigger 9, whereby said latch is disengaged from 90 the pin 23.

The spark-producing elements comprise a rotary bur-wheel 27 and a piece of pyrophoric material 28, which latter is loosely arranged in a tubular holder 29, secured at 95 its upper end to the bracket 13.

The tubular holder 29 has two diametrically opposed longitudinal slots 30, through which one arm of a spring 31 projects for the purpose of taking up wear of the element 28 and holding it in frictional engagement with the bur-wheel 27. The intermediate portion of spring 31 is coiled about a stud 32 projecting from a lug 13^a, at the lower end of the bracket 13, against which 105 one end of said spring 31 abuts. The end

of the spring 31, passing through the slots 30, is formed into a handle 33, whereby it may be readily grasped and pushed downward out of the holder 29 when it is necessary to provide the same with an element 28.

The bur-wheel 27 is fixedly-mounted upon a short shaft 34, journaled in the bracket 13 and provided at one end with a rigidly mounted ratchet-wheel 35, which is actuated by a ratchet-bar 36, pivotally-mounted upon a stud 37, projecting inwardly from one of the cheeks 15. The ratchet-bar 36 is yieldingly-held in engagement with the ratchet-wheel 35 through the intermediacy 15 of a spring 38, coiled about the stud 37 and having one end connected to said ratchet-bar and its other end to the stud 37.

In order to ignite the wick, the hand-wheel 8 is grasped and rotated in the direction of the arrow, Fig. 2. This operation winds the spring 19 and causes the forward end of the trigger 9 to rock upward into engagement with the cam-shaped terminal 26 of the latch 21, which latter prevents the 25 cheek-plates 15 from rocking forward during the initial movement of the hand-wheel 10. As the forward end of the trigger 9 rocks upward into engagement with the cam-shaped portion 26 of the latch 21, the 30 latter is released from the pin 23 and permits the cheek-plates 15 to be thrown suddenly backward by the spring 19 until the spacing sleeve 18 contacts the extension 5.

As the cheek-plates 15 swing backward and 35 downward, they carry the ratchet-bar 36 therewith, which rotates the ratchet-wheel at high speed and causes it in turn to rapidly rotate the bur-wheel 27, which scrapes against the upper end of the element 28 and 40 produces a spark. The spark thus produced ignites the upper end of the wick which has been exposed, owing to the upward movement of the snuffer 11, which was raised to the position indicated by Fig. 2, through the 45 intermediacy of the trigger 9 and the connecting-bar 10. In order to extinguish the flame, the hand-wheel 10 is released, when the parts are immediately restored to normal position through the intermediacy of 50 the spring 19. As the snuffer swings down upon the upper end of the extension 5, it covers the upper end of the wick A and smothers the flame.

Having thus described my invention, what

I claim and desire to secure by Letters Patent, is:

1. A cigar lighter comprising a wick holder, a rock shaft pivotally associated therewith, cheek plates pivotally connected to the shaft, a trigger fixed to the shaft, a latch pivotally connected to one of the cheek plates, said latch having a cam formed upon one end and normally engaged by one end of the trigger, a pin mounted adjacent the wick holder and normally engaged by the other end of the latch, means for swinging the cheek plates downwardly to disengage the latch and trigger, resilient means for swinging the cheek plates upwardly, whereby the trigger again engages the cam of the latch bar to regulate the swinging movement of the cheek plates, and frictional igniting means adjacent the wick for igniting the same during movement of the cheek plates in one direction. 75

2. In combination with a wick holder, a spring actuated carrier pivotally associated with the holder, a latch pivotally connected to the carrier, a trigger having one end normally engaged with one end of the latch, means for normally holding the latch against pivotal movement, said trigger being adapted to gradually disengage the latch to tension the spring when the carrier is swung downwardly, and friction igniting means adjacent the wick for igniting the same during downward movement of the carrier. 80

3. In combination with a wick holder and igniting means therefor, a rock shaft pivotally supported thereby, a trigger fixed to one end of the rock shaft, a carrier pivotally supported by the shaft, a spring yieldably connecting the carrier and shaft, a latch pivotally connected to the carrier, and having one end normally engaged with the trigger, a pin mounted adjacent the holder and normally engaged by the other end of the latch, and means for rocking the shaft to tension the spring subsequent to the disengagement of the trigger and latch, and the latch and 95 pin. 100

In testimony whereof I affix my signature, in the presence of two witnesses.

HARRY W. CLARK.
